UNITED STATES PATENT OFFICE.

NORRIS E. BRAY, OF KIMBALL, SOUTH DAKOTA.

GRAIN DOOR FOR FREIGHT CARS.

Application filed July 14, 1926. Serial No. 122,432.

This invention is a grain door for freight cars, the object being to provide a closure which, when in use, will completely cover the door opening so as to prevent the escape 5 of grain and, when not in use, will be stored within the roof of the car out of the way so as to leave the entire interior free for the placement of other freight. Other objects of the invention are to provide means for 10 effectually restraining the door members against movement when they are stored in the roof of the car, and to provide a construction of door section which will prevent binding of the door sections at the door opening when in use and counteract any tendency 15 of the door sections to warp. These stated objects, and other objects which will incidentally appear in the course of the following description, are attained in such a structure as is illustrated in the accompanying drawings, and the invention resides in certain novel features which will be particularly pointed out in the appended claims.

In the drawings:

Figure 1 is a transverse section of a car body showing my improved door in closed position at one side and in open stored position at the other side;

Fig. 2 is a longitudinal section on the line 30 2-2 of Fig. 1;

Fig. 3 is an enlarged detail perspective view of one end of a door section;

Fig. 4 is an enlarged detail perspective view of a step;

Fig. 5 is an enlarged detail perspective view of a stop bracket for retaining the door sections in the stored position.

The car body 1 may be of any approved form and is illustrated in a conventional 40 manner only, the numeral 2 indicating the usual outside doors which are mounted for sliding movement upon the sides of the car to be supported at the side of the door opening or extend over the same in the usual 45 manner. In carrying out the present invention, I provide transverse girders 3 at the roof of the car and substantially aligned with the sides of the door openings therein, and upon the medial longitudinal line of the car 50 a vertical partition 4 extends between the said girders. The door posts 5 are rabbeted upon their edges and to the inner sides of the posts are secured track irons 6 which project somewhat beyond the inner sides of 55 the rabbeted portions of the door posts so as to coat with the door posts to define

grooves in which the door sections may be received. The track irons are curved inwardly at the upper ends of the door openings, as shown at 7, and are then continued inwardly along the lower edges of the girders 3, as shown at 8, to points immediately adjacent the lower edge of the partition 4 where they are curved upwardly, as shown at 9, the inner extremities of the track irons being extended vertically and secured to the opposite sides of the partition, as shown at 10. It should be noted, however, that the partition 4 may be omitted and the upturned terminals of the track irons secured to the adjacent girder 3. Upon the upper sides of the horizontal portions 8 of the track irons are spaced stops or lugs 11 which have convex upper surfaces and the purpose of which will presently appear. The grain door comprises a plurality of sections 12 which are of rectangular form and of such length that, when in use, they will extend entirely across the door opening with their ends resting between the track irons and the vertical shoulder on the door posts. The sections may all be of the same vertical dimension but I prefer to make them in graduated heights to facilitate their storage below the roof of the car, it being noted that the car lines diverge downwardly from the center toward the sides of the car, as shown in Fig. 1, so that the space between the portions 8 of the tracks and the roof of the car is gradually contracted toward the 90 sides of the car. The lowermost section 12 has its lower edge in one plane and the upper edge of the uppermost section is also in one plane. The remaining edges of all the sections are rabbeted so as to present a square shoulder or step form, as shown at 13, the rabbet or recess being at the inner side along the top edge of a section and at the outer side along the lower edge of the section. This formation, as shown clearly 95 in Fig. 1, provides a square support for the several sections when they are in use so that they cannot wedge or bind between the door posts and the track while at the same time they form a completely closed joint to prevent leakage of the grain. In each end of each section is inserted a sheet metal plate 14 which will counteract any tendency of the sections to warp so that they will always be in condition to enter easily between the track irons and the shoulders of the door posts. These plates 14 have their end por-

tions 140 extended over the vertical faces of the rabbets in the door sections, as shown in Fig. 3, and carried over the edges of the section and the sides of the same. The terminals of the plates seat flush in the edges and sides of the door sections but necessarily project slightly from the vertical faces of the rabbets, the projections, however, being immaterial in respect to the fit of the door or the grain-tight quality of the joint. The plates protect the corner of the sections which might, otherwise, be broken off under hard usage. In the outer face of each section, adjacent the ends thereof, are recesses 13 or grooves 15 which constitute finger holds to facilitate the raising of the door sections when the contents of the car are to be removed.

The stops 11 are so spaced that the lower edge of a door section may be received between each two stops, and correspondingly spaced brackets 16 are secured upon the sides of the girders 3 immediately below the car roof to accommodate the upper edges of the door sections so that the said sections will be firmly supported and held when they are not in use. I also provide dogs 17 which are pivoted upon the sides of the girders 3 adjacent the upper portions of the track irons 7 and immediately over the curved portions of the same. These dogs 17 are provided in their lower edges with shoulders 18 adapted to engage behind the outer edges of the door sections resting upon the horizontal portions 8 of the tracks, and the lower outer ends of the dogs are beveled or curved, as indicated at 19, so that, when a section is pushed against a dog, the dog will be moved upwardly and permit the section to ride under the same, the dog automatically dropping to engage the outer edge of the section when it is cleared by the section, as will be understood upon reference to Fig. 1. Above and inwardly from the dogs 17 are gravity stops or latches 20 which are somewhat elongated plates or thin bars provided with obliquely disposed slots 21 through which supporting pins 22 are inserted to slidably secure the latches to the girders. When the door sections are in place, the inner end of the respectively adjacent latch 20 will bear against the outer side of the outermost door section so as to aid in holding the same in place, and it will be noted that the inner end of each latch is beveled, as at 23, to facilitate the upward movement of a door section past the latch while the inclined arrangement of the slots 21 will permit the weight of the latches to cause them to slide toward the door sections and operatively engage the same.

Fitted in the side 24 of the car body is a step which consists of a bar or rod bent into U shape, as shown at 25, and having the legs of the U fitted through inclined slots or

openings 26 formed through the side of the car. Wear strips 27 are secured to the inner and outer faces of the car wall 24 adjacent the ends of the openings 26 to receive the wear of the step and thereby prevent splintering or chipping of the wood employed in the building of the car wall. It will also be noted that the terminals of the step are turned upwardly, as indicated at 28, to constitute stops engageable with the outer wear plate 27 and thereby limit the extent of inward movement which may be imparted to the step. When the grain door is to be stored in the roof of the car, the step 25 is pulled upwardly so as to assume the position shown in Fig 4, and the operator may then stand upon the step while pushing the several door sections into the storage space. To provide further support for the operator, a hand-hold or grip 29 is secured to the side beam 30 of the car immediately adjacent the door opening so that the operator may obtain a grip with one hand upon the said hand-hold 29 while leaving his other hand free to manipulate the door sections.

As shown and as before stated, when the door opening is to be closed, the several door sections are brought into superposed relation between the tracks and the door posts so as to extend across the door opening. The door opening at one side of the car may be completely closed before the filling of the car with grain is started and at the other side sections may be placed in position successively as the height of the grain within the car increases so that by the time the car has been completely filled the door openings at both sides will be closed. When moving the door sections into position across the door opening, the operator may be provided with a hook rod or other convenient tool which may be engaged against the outer end of the corresponding dog 17 so as to lift the dog and permit the sections engaged thereby to be moved outwardly and downwardly. As additional sections are required, the hook rod may be engaged about the lower edge of the successive sections so that a pull thereon will move the lower edges of the sections over the stops 11 and free the sections from the latches 20. These sections may then be successively pulled outwardly over the tracks and dropped into place upon the previously arranged sections. When the car is to be opened so that the grain may be removed, a lifting force applied to the lowermost sections and against the upper edges of the recesses 15 will effect upward movement of all the sections, and any convenient chock may be placed under the raised sections so that the grain may be permitted to flow through the opening thus established at the lower end of the door. When the car is emptied and is to be returned to its starting point, or other freight is to be placed therein, the operator,

by applying a stick or other convenient implement to the several sections successively, may push them onto the upper portions of the track and as the uppermost section reaches the curved portion 9, it will be deflected upwardly into a nearly vertical position so that its upper edge will engage behind the brackets 16 and its lower edge will engage behind the innermost stops 11. Each succeeding section will be likewise turned upwardly by having its inner edge ride against the lower edge of the previously stored section and the last sections may be permitted to remain upon the horizontal portion of the tracks, as shown in Fig. 1, and held against release by the dogs 17. In order to move the several sections to the inner limit of the space, the operator will pull the step 25 upwardly and inwardly so that he may stand thereon and be in a position to push the sections to the inner end of the available space under the car roof. When all the sections have been stored, as indicated in Fig. 1, the operator merely moves off the step 25 and the weight of the step, coacting with the jarring of the same due to the travel of the car, will cause the step to move downwardly in the openings 26 so that the shoulder portion of the step may seat in a groove 31 provided therefor in the side of the car wall and thus be out of the way of grain or other freight which may be placed in the car.

From the foregoing description, taken in connection with the accompanying drawings, it will be seen that I have provided an exceedingly simple and efficient grain door for the door openings of freight cars which, when in use, will provide a complete closure for the door opening and when not in use will be disposed in very compact form within in the roof of the car so as to leave the interior of the car entirely free of obstructions.

Having thus described the invention, I claim:

1. The combination with a freight car including transverse girders disposed at the roof of the car and extending between the sides of the opposite door openings, door sections adapted to extend across the respective door openings in superposed relation and to move into a position between the girders, elements at the lower edges of the girders to deflect the door sections moving thereover into approximately upright positions, and means on the girders to engage the sections and retain them in such approximately upright positions.

2. The combination with a freight car, of

transverse girders at the roof of the car and at the sides of the door opening in the car, a plurality of door sections movable to extend across the door opening or to positions between the girders, means for deflecting the sections into approximately upright positions between the girders, brackets on the girders to engage behind the outer faces of the several sections, and means mounted on the girders to restrain the sections against outward movement.

3. The combination with a freight car, of girders at the roof of the car and at the sides of the door opening therein, a plurality of door sections movable to extend across the door opening or to positions between the girders, means on the girders for turning the door sections into approximately upright positions between the girders, means for supporting the door sections in the upright positions, and latches slidably mounted on the sides of the girders to engage the outermost door sections and restrain them against outward movement.

4. In a freight car, the combination of transverse girders at the roof of the car and at the sides of the door opening, a plurality of door sections movable to extend across the opening or to extend between the girders, supports on the girders for the door sections, means to turn some of the door sections into approximately upright position between the girders, a gravitating latch slidably mounted on the girders to engage the outer upright sections and retain them against outward movement, and dogs pivoted on the girders to engage against the outermost sections and restrain them against outward movement.

5. In a freight car, the combination of transverse girders at the roof of the car and at the sides of the door opening, a plurality of door sections movable to extend across the opening or to extend between the girders, supports on the girders for the door sections, stop lugs at the lower edges of the girders to engage the lower ends of some of the door sections and retain them against outward movement, stop brackets on the girders in the upper portions thereof to engage the upper edge portions of the door sections, gravitating latches mounted on the sides of the girders to engage against the outermost upright door sections, and dogs pivotally mounted on the girders outwardly below and beyond the latches to engage the outermost door sections whereby to retain all the sections against outward movement.

In testimony whereof I affix my signature.

NORRIS E. BRAY. [L. s.]
